US0D1068389S

(12) **United States Design Patent** (10) **Patent No.:** **US D1,068,389 S**
(45) **Date of Patent:** **** Apr. 1, 2025**

(54) **STACKABLE MUG**

(71) Applicant: **Aakron Rule Corp.**, Akron, NY (US)

(72) Inventor: **Danielle Robillard**, East Aurora, NY (US)

(73) Assignee: **Aakron Rule Corp.**, Akron, NY (US)

(**) Term: **15 Years**

(21) Appl. No.: **29/896,946**

(22) Filed: **Jul. 10, 2023**

(51) **LOC (15) Cl.** **07-01**

(52) **U.S. Cl.**

USPC **D7/533**

(57) **CLAIM**

The ornamental design for a stackable mug, as shown and described.

DESCRIPTION

FIG. 1 is a perspective view of the stackable mug showing my new design;

FIG. 2 is another perspective view thereof;

FIG. 3 is a right side elevation view thereof;

FIG. 4 is a rear elevation view thereof;

FIG. 5 is a left side elevation view thereof;

FIG. 6 is a front elevation view thereof;

FIG. 7 is a top plan view thereof; and,

FIG. 8 is a bottom plan view thereof.

The broken lines in the drawings depict portions of the stackable mug that form no part of the claimed design.

1 Claim, 7 Drawing Sheets
